UNITED STATES PATENT OFFICE.

EDMUND L. ZALINSKI, OF THE UNITED STATES ARMY, AND HENRY JULIUS SMITH, OF POMPTON, NEW JERSEY.

DELAY-ACTION PRIMER.

SPECIFICATION forming part of Letters Patent No. 405,647, dated June 18, 1889.

Application filed November 23, 1888. Serial No. 291,679. (No model.)

To all whom it may concern:

Be it known that we, EDMUND L. ZALINSKI, of the United States Army, stationed at Fort Hamilton, New York, and HENRY JULIUS SMITH, residing at Pompton, in the county of Passaic and State of New Jersey, have invented certain new and useful Improvements in Delay-Action Primers, of which the following is a specification, reference being had 10 therein to the accompanying drawings.

This invention relates to electric fuses of the kind used in mining, blasting, &c.

The invention consists in the construction and interposition of a delay-action piece between the ignitor or primer and the detonator.

In blasting and mining operations, especially in tunnels and shafts, it is frequently desirable to place a large number of blasting-charges in proximity, so that a central group can be fired, breaking up or loosening a central core by a "shot" or blast, and then by a succeeding shot of a group near or surrounding this core the rock or ore is thrown toward or into the space thus created. This is usually done at two operations; but such a series of steps is inconvenient and often dangerous. It will be apparent that the first explosion will be likely to break the delicate electrical connections if all the blasts are charged. Hence it is not expedient, if not impossible, to fire one set of blasting-charges (as of the core) by one battery-impulse and another or second set by another impulse. It is very desirable 35 to ignite all the charges at once, but cause them to explode in succession. With this object in view we provide a delay-action fuse between the primers or ignitors and the detonators of some or all the blasts of a group, by 40 the use of which all the charges may be ignited simultaneously, but the explosions will take place successively.

Referring now to the drawings, Figure 1 illustrates a section of a delay-action or time primer or fuse in its relation to the ignitor and detonator, the delay-action piece being made detachable. Fig. 2 is a sectional view of a similar fuse connected to the detonator. Fig. 3 is a section similar to Fig. 2 with the ignitor 50 omitted. Fig. 4 is a section of the delay-ac-

tion fuse made integral with the ignitor, and Fig. 5 is a section of a delay-action fuse with metallic casing.

The letters *a a'* indicate the conducting-wires, which are insulated in usual manner, 55 as by textile covering *b*. The ends of the wires are connected by a platinum bridge or similar bit of wire, which becomes heated by the passage of electricity in the usual manner. Surrounding or in proximity to this 60 bridge there is a small igniting-charge *c*—say of fulminate of mercury. This may be inclosed in a casing of plastic or other material, as indicated by the letter *A*, Figs. 1 and 2.

B indicates a plug or piece of wood, paper-pulp, plaster, or other material, having a passage *d*, which leads from the seat *e* for the primer to the end of the plug. The passage *d* is filled with mealed powder or other slow-burning composition in such quantity as is 70 desirable to burn for the desired interval of time, usually but a fraction of a second. The passage *d* may have vent-apertures *g*, which are filled with wax, tallow, or similar material, and by preference the entire block *B* is 75 covered with a coat of such waterproofing material as can be readily done by dipping.

The modification shown in Figs. 2 and 3 is such a structure as results from taking the lower end *B'* of the plug *B* and inserting it 80 permanently in the casing of the detonator *D*, leaving a space above the same to contain the ignitor.

In Fig. 4 the passage *d* is in the sulphur or other piece *A'*, which forms the inclosing-casing *A*, the passage *d* having one end in close proximity to the igniting-charge at *c*.

In Fig. 5 *A'* indicates a delay-action fuse-piece in a metallic casing instead of the plug *B*, this casing being ready to receive the ignitor at one end and convey the fire therefrom to the detonator.

The lower end of the passage *d*, Figs. 2, 3, and 4, and the top of the slow-burning charge in the passage *D* should be protected by a 95 coating of varnish, wax, rubber, or other waterproofing and inclosing material, as at *h h*, and the entire piece *B* may be covered with such material by dipping in the varnish or wax. The wax will serve to retain the 100

ignitor, delay-charge holder, and detonator together, and will surely seal all joints against moisture.

It will at once appear that the construction of this delay-action charge-holder may vary, the generic idea being that a delay-action charge shall be interposed between the igniting and detonating charges, and the species considered most important, herein described, is that in which the delay-action charge-holder is separable from the detonator and capable of separate shipment and use.

It will be readily understood that such charge-holders may be made to contain such a quantity of slow-burning powder as will secure the necessary interval between the ignition and explosion, be the same more or less.

The commercial detonator is usually a metallic tube open at one end and closed at the other and containing ten to thirty grains of fulminate of mercury near the closed end. Such detonators are procurable in most mining regions and are well known to the trade.

What we claim is—

- 25 1. The combination, with an electric ignitor and a detonator of the character described, of an interposed delay-action primer or time-fuse, substantially as described.
2. A delay-action primer consisting of a charge-holder chambered to receive an elec-

trical ignitor and shaped to fit a commercial detonator and having a slow-burning or time charge contained in said holder, substantially as stated.

3. A delay-action primer consisting of a 35 charge-holder having vents, a time-charge contained in said holder, a chamber to receive an electrical ignitor in proximity to said charge, and being shaped to fit the commercial detonator, substantially as described. 40

4. The combination, with the charge-holder of a shape to fit the detonator and having a chamber for the ignitor, of a time-charge contained in said holder with a water-proof coating covering said burning charge. 45

5. The combination, with an electric ignitor and a detonator, of a separate delay-action charge-holder shaped to connect both.

6. The delay-action charge-holder described chambered to receive the ignitor, shaped to fit the commercial detonator, and covered with a coating of water-proof material, substantially as described. 50

In testimony whereof we affix our signatures in presence of two witnesses.

EDMUND L. ZALINSKI.
HENRY JULIUS SMITH.
